LOCOMOTIVE DRAFT APPLIANCE

Application filed December 18, 1923. Serial No. 681,450.

This invention relates to locomotive draft appliances and it has for one of its primary objects the efficient drafting of the locomotive with minimum back pressure in the cylinders, whereby the efficiency of the locomotive is increased.

Another object of our invention is the provision of an effective means for drafting a locomotive as a substitute for the customary exhaust steam blast used for the creation of the draft. In this connection our invention contemplates the creation of the draft by means of a fan, and while we are aware that heretofore it has been proposed to use a fan for this purpose, yet in so far as we know no practical device of this character has hitherto been employed.

Another object of our invention is to provide a draft device of the fan type the capacity of which can be readily altered to suit the requirements of any particular locomotive, so that one or two sizes will suffice for practically all locomotives.

A further object of our invention is to provide an improved combined draft appliance and feed water heater.

More specific objects and advantages will be hereinafter set forth in connection with the description of the invention.

How the foregoing, together with such other objects and advantages as may be incident to our invention, are obtained, is illustrated in the accompanying drawings showing the preferred embodiments of our invention, and in which

Fig. 1 is a vertical cross section through a locomotive front end or smoke box showing the application of our improvement;

Fig. 2 is a vertical section through the bearing means for the fan shaft, taken on the line 2-2 of Fig. 3 and illustrating the method of protecting the same and their lubrication;

Fig. 3 is a section taken on the line 3-3 of Fig. 2;

Fig. 4 is a vertical section through the feed water heater proper; on the line 4-4 of Fig. 1;

Fig. 5 is a section taken on the line 5-5 of Fig. 4;

Fig. 6 is a top plan view of a detail of the heater;

Figs. 7, 8 and 9 are views illustrating details of the turbine nozzle, Fig. 8 being taken on the line 8-8 of Fig. 7;

Fig. 10 is a partial plan and section of the fan;

Fig. 11 is a curve, illustrating certain principles involved in our invention, and Fig. 12 illustrates a detail of the device.

Referring now to Fig. 1, the reference character A indicates the front end or smoke box of the locomotive, while the reference character B illustrates our combined stack, heater and draft appliance.

This draft appliance takes the place of the usual stack, although of considerably larger size. In general it comprises the fan 7, the feed water heater proper C, the economizer D, and the turbine driving mechanism E.

The fan 7 is of the centrifugal type as we have found that, for this purpose, the ordinary fan having the radial blades with straight pull and discharge, is not as effective. The fan comprises the hub 8; the upper disc or wall 9; the lower wall 10 spaced away from the wall 9 to provide the laterally directed discharge throat 11; and the blades or impellers 12, secured to the walls 9 and 10, as illustrated in Fig. 10. All portions of the blades, with the exception of the attaching flanges, are vertical. The wall 10 is provided with an inner rim or neck portion 13 upon which the buckets 14 of the turbine drive are mounted. A shroud 15, if necessary, may be placed around the fan to assist in deflecting the exhaust from the fan upwardly to clear the cab. The hub may be provided with a plurality of tapped openings 16 for the insertion of balancing plugs, the matter of proper balance being an important consideration.

The fan 7 is mounted on the shaft 17. This shaft depends in the innermost of three nested shells or housings 18, 19 and 20. The housing 20 is welded or otherwise securely attached to the tube sheet 21 of the economizer D. The shell 19 is suspended within the housing 20 from the top thereof, being welded

55

60

65

70

100

or otherwise secured thereto. A dead air space 22 is provided between these housings or shells to insulate the shaft and its bearings from the heat of the front end. The housing 18 is provided with laterally extending lugs 18^a at the top and bolted to the housing 20 by means of the bolts 23.

The housing 18 is provided with vertical ribs 24 cooperating with the shell 19 to provide vertical channels communicating at the bottom with the space 25 between the housing 18 and the shell 19. A disc 26 is secured over the top of the housing 18 and is provided with three slots 27 in line with three of the channels formed by the ribs 24. The other three channels are blanked off at the top by the disc, as will be clear from Fig. 3. The hub of the fan is provided with a plurality of apertures 28 above which the small fan blades 29 are disposed so as to force air downwardly through such apertures into the space 30 and down through the slots 27 in the disc 26, the air thence flowing downwardly through three of the channels about the housing 18 and then upwardly through the other three channels and thence outwardly between lugs 18^a, as indicated by the arrows in Figs. 2 and 3. This circulation of air is brought about by the fan blades 29 and the fact that three of the channels around the housing 18 open laterally into the low pressure area of the fan 7. Thus the fan in operation sets up a cooling circulation of air around the housing 18. The shaft and its bearings are, therefore, further protected from the heat of the front end.

The shaft is provided with a radial bearing 31 at the top and with a combined radial and thrust bearing 32 at its lower end, both bearings being carried within the housing 18. The housing 18 is filled with oil to about the level indicated in Fig. 2, the oil being introduced through the shaft 17 which is made hollow for this purpose. The oil is circulated in the following manner.

As the shaft revolves, the oil within the central opening therein wells up in parabolical form and begins to flow out laterally through the inclined port 33 from which it is discharged by centrifugal force into the vertical grooves 34 of the sleeve-like member 35 surrounding the shaft, and extending between the bearings. These grooves increase in depth upwardly so that centrifugal force continues to lift the oil, discharging it out through the one or more apertures 36 in the top of the sleeve 35 just beneath the bearing 31. The oil passes through such bearing, lubricating the same and, if it overflows into the space 37 above the bearing, it is returned to the bottom or sump portion of the housing 18 by means of the port 38, lubricating the bearing 32 in its passage downward. If the oil be kept at the proper level, the bearings 32 will also be lubricated from beneath while at rest only.

It will thus be seen that the shaft and its bearings are protected by the dead insulating space 22, by the flow of air through the channels around the housing 18 and by the circulation of the oil within the housing 18, whereby overheating, which is one of the most serious problems in connection with apparatus of this character, is overcome. Immediately above the bearing 31 we provide a pad 39 which becomes soaked with oil insuring lubrication of the bearing 31 in starting the fan. This is advantageous in the event that the locomotive is idle for any length of time.

In order to maintain a predetermined level of oil within the housing 18, we provide a float 40 on the stem 41, the upper portion of which fits into the plug 42, acting as a valve to shut off further oil admission when there is a proper level of oil within the housing. The plug 42 is hollow and receives a strainer 43, the opening being closed by the plug 44. This arrangement is effective to prevent the ingress of any dirt into the housing 18.

The bearing 32 is positioned between the annular lip 45 and the sleeve 35, while the bearing 31 is positioned between the sleeve 35 and the collar 46 which in turn is clamped by the hub of the fan and the nut 47. In this connection the length of the sleeve 35 is such that when the nut 47 is tightened, the sleeve 35 will be under some measure of compression thereby securely supporting both bearings. The top of the housing 18 is closed by a cap plate 48 and a packing 49 is provided between such plate 48 and the collar 46 to prevent dirt working its way within the housing 18. Depending from the lower face of the hub is an annular ring or rib 50 serving to enshroud the top of the housing 18.

By removal of the fan and the bolts 23, the fan shaft and bearings and the housing 18 may be removed as a unit.

Coming now to the economizer D, it will be seen that this comprises the upper tube sheet 21 hereinbefore referred to; the shell 51; the bottom tube sheet 52 and the nest of tubes 53, the lower ends of which open into the smoke box and the upper ends into the low pressure area of the fan. The tubes 53 are arranged in annular rows, the diameter of the tubes of the various rows being successively smaller. By this arrangement it is possible to greatly increase the number of tubes, as the result of which a maximum area of heat transferring surface is obtained.

The smoke box gases are drawn through the tubes 53 and discharge laterally outward and upward from the fan, and, in passing through the tubes, they give off appreciable heat to the feed water in the economizer, such feed water passing from the heater C thru the outlets 54 into the economizer drum. It will be observed on inspection of Fig. 1 that the outlets 54 discharge about midway of the height of the economizer, as a result of which

there is a downward and then an upward circulation of the water in the economizer. The feed water is taken from the upper portion of the economizer drum by means of the pipes 55 in order to prevent the formation of any air pockets in the drum. The pipes 55 of which there may be any desired number lead to a header 56 from which pipes lead outwardly through the smoke box shell to the injectors (not shown). For cleaning out purposes, pipes 57 lead from the bottom of the economizer drum to the exterior where they are provided with blow off cocks 58. The economizer drum is suspended in the front end by means of the steam chest or manifold 59 resting upon and secured to the front end shell, as will further appear.

The heater C will now be described. This heater includes the shell 60 which is welded to the bottom portion of the housing 20 and to which, in turn, the bottom tube sheet 52 of the economizer drum is welded. The lower end of the casing 62 has a flange 61 which serves as a means for positioning the heater casing 62 through the medium of the ring 63 and the studs 64 as will be clear from inspection of Fig. 4. The casing 62 carries at its top a tube sheet 65 and at the bottom there is another tube sheet 66 which, however, is 30 flexibly carried in the manner to be described. The lower end of the casing 62 is open and is adapted to be closed by the cap or end plate 67 and the flexible diaphragm 68, such diaphragm being clamped between the tube sheet 35 66 and the plate 67 and between the bottom of the casing 62 and the ring 69. The plate 67 and the tube sheet 66 thus cooperate to form a header which is flexibly mounted with respect to the casing 62 to take care of expansion and contraction of the nests of tubes 70, the ends of which are expanded or welded in 40 the tube sheets 65 and 66.

Feed water is introduced into the header formed by the plates 67 and the tube sheet 66 through a suitable pipe 71 secured to the inlet 72. The interior of the header is divided into two compartments 73 and 74 by the division wall 75, the upper end of which takes against the tube sheet 66. The entering feed 50 water passes through compartment 73 and upwardly through the nest of tubes opening from such space into the compartment 76 formed by the plate 77. From this compartment 76, feed water flows down the next pass 55 or nest of the tubes leading downwardly from such compartment to the compartment 74. From compartment 74 the feed water passes through the third or last pass upwardly into the space 78, from which space most of the 60 feed water discharges through the openings 54 before described, although a portion may also flow downwardly and outwardly through the discharge ports 54a.

The feed water is heated by exhaust steam 65 introduced into the casing 62, the steam be-

ing supplied by means of the elbow 79, the lower end of which is fastened to the usual nozzle stand base 80 of the saddle casting, whereby exhaust steam from the cylinders enters the casing. Exhaust steam from the auxiliary engines may be led to the casing by means of the pipes 81. The entering steam flows upwardly toward the upper part of the casing and then downwardly over the baffle 82, this baffle being provided for the purpose of securing a circulation of steam and the elimination of any dead spaces. The outlet of the casing 62 is indicated at 83 in Fig. 1, from inspection of which it will be noted that such outlet is of comparatively restricted character. By virtue of this restricted outlet only so much steam as can be properly condensed in the feed water heater flows into the heater casing. The use of more steam than is required for this purpose is unnecessary, would introduce complications in the disposition of the surplus steam, and would diminish unnecessarily the volume available for driving the draft fan hereinafter to be described.

With reference to the tubes 70, as before described, they are arranged in three parallel passes, one succeeding another transversely of the heater. Ordinarily the tube nests are disposed according to a radial or segmental arrangement of passes, the first and last of which are beside one another and have a maximum temperature difference, representing the difference between the initial temperature and the final temperature. As a result, two adjacent nests of tubes have to accommodate an expansion caused by a maximum temperature difference. By our arrangement of parallel succeeding sections or passes, the water flows progressively from one to the next with the result that the total temperature difference is divided by three. Thus a minimum difference in expansion exists between two adjacent sections. With this minimum difference in expansion, the stresses are kept well within the elastic limit of the tubes. However, by virtue of the diaphragm 68, the lower tube sheet has a capacity to tilt and weave a slight amount thereby reducing the stresses in the tubes to a very appreciable extent.

The housing 20 and the shell 60 cooperate to constitute a central strength member for the economizer drum.

Referring now to the turbine and particularly Figs. 1, 7, 8, 9 and 12, it will be seen that the steam chest or manifold 59 is open at the top and has secured over such open top, a nozzle ring 84, provided with a plurality of nozzles 85. The nozzle has a bowl portion 86, a throat 87 and a mouth 88. The nozzle passages have their upper and lower surfaces defined by the steel plates 89, provided to extend the life of the turbine. A number of

tapped holes 90 are provided in the nozzle ring for the purpose of securing a blanking strip or strips over certain of the nozzle mouths, an arrangement affording a means for altering the capacity of the turbine and fan to suit the requirements of the particular engine, thus making one size capable of wide application. The buckets 14 are of usual construction.

10 Exhaust steam is led to the turbine chest from each steam chest of the locomotive by a pipe 91. The cross sectional area of the pipes 91 is such as to conduct the exhaust steam freely to the manifold 59, and the total area 15 of the nozzles, due to their number, resulting from the large diameter of the turbine, is such that the maximum back pressure in the main engine cylinders will be very low as compared to standard practice, say, for example, in the 20 neighborhood of $2\frac{1}{2}$ to 3 pounds.

The turbine is intentionally designed to operate at such low pressure, preferably at 2.4 pounds per square inch. With this low pressure we are enabled to obtain maximum nozzle and bucket efficiency as will be clear from the following. For the particular class of service, the fan should not operate at too great speed and we have so designed the apparatus that the peripheral speed of the buckets 30 mounted adjacent the fan periphery at rated load, should be approximately 350 ft. per second. The nozzle and bucket efficiency will increase with increase of the velocity ratio, i. e., bucket speed over steam speed. With a 35 pressure in the fan steam chest or manifold of 2.4 pounds per square inch exhausting to the atmosphere, the velocity of the steam will be approximately 744 ft. per second. If now the curve of Fig. 11 be examined, it will be 40 seen that the velocity ratio (bucket speed divided by steam speed) equals .47, at which the nozzle and bucket efficiency is a little below 45 80 per cent. By way of comparison if we assume a pressure of 200 pounds per square inch in the manifold exhausting to atmosphere, the velocity of the steam would be 3120 ft. per second giving a velocity ratio of .112 and a nozzle and bucket efficiency in the 50 neighborhood of 30 per cent.

50 It will be seen, therefore, that with the permissible fan speed it is essential, in order to have a practical device, to operate the turbine with very low pressure, and to design the fan to provide adequate draft at the speeds at 55 which maximum efficiency of the nozzle and buckets can be obtained. The combination of the large-diameter, low pressure operated turbine and the large-diameter, axial-intake 60 and centrifugal-discharge fan obtains the desired results. In this connection it should again be noted that both fan and turbine are mounted on top of the smoke-box at the stack outlet, and are therefore unrestricted by the 65 inherent space limitations of the same. In

other words, by mounting the fan and its driving means as shown, their diameter may be increased beyond what has heretofore been possible in the art, with the result that unrestricted intake and discharge areas are possible for the fan, and lower steam pressures may be used on the turbine, which gives greater nozzle and bucket efficiencies as hereinbefore set forth, and as shown in Fig. 11.

In order to operate the fan at times when no exhaust steam is available for such purpose and also in order to obtain a maximum degree of flexibility, we provide means for supplying boiler pressure steam to the turbine. For this purpose we provide one high pressure nozzle 96 in the nozzle ring 84, having a bowl portion 96', communicating with a special cavity 92 in the manifold 59, to which cavity high pressure steam is conducted by means of the pipe 93. This is illustrated in Fig. 12. This single high pressure nozzle will develop approximately one-quarter of the power of the low pressure nozzles and thus the fan may be operated when the locomotive is standing or is about to be started. Similarly at times of high overload, the high pressure nozzle may be used to supplement the low pressure nozzle affording the requisite flexibility of the draft appliance. Under ordinary conditions a draft blast will be produced proportionate to the amount of steam being used, automatically creating a draft appropriate for the particular operating conditions. The draft will be continuous, of large volume, and of low velocity, so that there will be no tendency to pull holes in the fire bed or exhaust sparks or cinders. In fact the usual front end netting, which is a source of great trouble and expense, may be dispensed with.

If needed as a provision against racing of the fan, an ordinary safety or relief valve may be attached to the steam chest at the point marked 94 in Fig. 12. For the purpose of supporting the economizer drum against 110 rotation we provide one or more studs 95 as shown in Fig. 1.

We claim:

1. In a locomotive draft appliance, a stack and an exhaust-steam-driven centrifugally discharging fan for producing draft, said fan being located at the stack outlet.
2. In combination with a locomotive and its smoke-box and stack, a turbine operated by the locomotive exhaust, and a draft fan driven by said turbine, approximating the smoke-box in diameter, and positioned astride said smoke box, axially of the stack, so as to be unrestricted in its effective intake and discharge area by the normal space limitations of said smoke box.
3. In combination with a locomotive and its smoke-box, an exhaust-steam-driven fan draft appliance, with at least the fan, proper,

thereof positioned without the confines of the smoke-box and approximating it in diameter, said draft appliance including a low-pressure exhaust-steam operated turbine positioned peripherally of the fan.

5 4. In a locomotive draft appliance, a stack, a centrifugal draft fan therefor mounted on a substantially vertical axis, and means around the periphery thereof for deflecting the discharge therefrom upwardly around it.

10 5. In a locomotive draft appliance, a stack, a centrifugal draft fan mounted on a vertical axis at the top thereof, and a shroud disposed peripherally of the fan and spaced 15 away therefrom.

20 6. In a draft appliance having a fan runner and bearing means therefor with air-channel means associated therewith, auxiliary fan blades on said runner positioned to circulate a draft of cooling air through said channel means to the intake side of the fan.

25 7. In a locomotive draft appliance, a stack, a draft fan revolving about a substantially vertical axis, a shaft therefor having bearings, a housing for said bearings mounted in said stack, and a second housing exterior of the first housing providing an insulating space therebetween.

30 8. In a locomotive draft appliance, a stack, a draft fan revolving about a substantially vertical axis, a shaft therefor having bearings, a housing for said bearings mounted in said stack, and a second housing exterior of the first housing providing an insulating space therebetween, together with means additionally subjecting said first housing to a cooling medium.

35 9. In a locomotive draft appliance, a stack, a draft fan revolving about a substantially vertical axis, a shaft therefor having bearings, a fixed housing for said bearings mounted in the stack, and means for circulating a cooling medium in contact with said housing.

40 10. In a locomotive draft appliance, a stack, a draft fan revolving about a substantially vertical axis, a shaft therefor having bearings, a fixed housing for said bearings mounted in the stack, and means for circulating a cooling medium exterior of the housing.

45 11. In a locomotive draft appliance, a stack, a draft fan revolving about a substantially vertical axis, a shaft therefor having bearings, a housing for said bearings, and means for circulating a cooling medium within and also exterior of the housing.

50 12. In a locomotive draft appliance, a stack, a draft fan revolving about a substantially vertical axis, a shaft therefor having bearings, a housing for said bearings, an oil bath in the housing, and means externally cooling the housing.

55 13. In a locomotive draft appliance, a stack, a draft fan revolving about a substan-

tially vertical axis, a shaft therefor having bearings, and three nested housings for said bearings providing an insulating space and a space through which a cooling medium may be applied.

70 14. In a locomotive draft appliance, a stack, a draft fan revolving about a substantially vertical axis, a shaft therefor having bearings, a housing for said bearings, and means whereby the fan sets up a flow of cooling air surrounding said bearings.

75 15. In a locomotive draft appliance, a stack, a draft fan revolving about a substantially vertical axis, a shaft therefor having bearings, a housing for said bearings, and means whereby the fan sets up a flow of cooling air exterior of the housing.

80 16. In a locomotive draft appliance, a draft fan revolving about a substantially vertical axis, a shaft therefor having bearing means, a housing around the shaft forming an oil reservoir, and means whereby oil may be introduced into the housing from the top of said shaft.

85 17. In a locomotive draft appliance, a draft fan revolving about a substantially vertical axis, a shaft therefore having bearing means, a housing for the shaft and bearing means the lower portion of which serves as an oil sump, and means associated with the shaft whereby the shaft when revolving lifts the oil, said means serving also to space the bearings.

90 18. In a locomotive draft appliance, a draft fan revolving about a substantially vertical axis, a shaft therefor having bearing means, a housing for the shaft and bearing means the lower portion of which serves as an oil sump, a conduit extending into the sump, and means associated with the shaft whereby the shaft when revolving lifts oil through said conduit.

95 19. In a locomotive draft appliance, a stack, a fan therefor and its shaft, a housing for the shaft, and means for supplying oil to the housing through the shaft controlled by the oil level.

100 20. In a locomotive draft appliance, a stack, a fan therefor and its shaft, a housing for the shaft, means for introducing oil to the housing, and an oil level indicating and shut-off float operating through said shaft.

105 21. A fan for drafting a locomotive comprising a fan runner rotatably mounted on said locomotive, said fan runner comprising a hub member extended into a dished web, vanes rigidly mounted on said web a dished cover rigidly fixed to said vanes, said web and said cover guiding the flow of exhaust gases from the furnace of said locomotive thru said fan runner in such a manner as to insure that the direction of flow of said gases at any point when leaving said fan runner has both axial and radial components, and means for driving said fan runner including a plurality of buckets mounted on said cover rigidly
